[57] CLAIM

The ornamental design for a combined optical coupler for coupling a television camera to an endoscope and an observation eyepiece therefore, as shown and described.

DESCRIPTION

FIG. 1 is a perspective view of a combined optical coupler for coupling a television camera to an endoscope and an observation eyepiece therefore showing our new design;

FIG. 2 is a side elevational view thereof, the opposite side being a mirror image;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view thereof on a reduced scale, the television camera and endoscope cable unit being shown in broken lines for illustrative purposes only.

FIG. 1

FIG. 2

FIG. 3

FIG. 4

FIG. 5

FIG. 6

FIG. 7
